UNITED STATES PATENT OFFICE.

ANDREW C. FARNSWORTH, OF CHICAGO, ILLINOIS.

PORTABLE FARE-COLLECTING APPARATUS.

SPECIFICATION forming part of Letters Patent No. 224,770, dated February 24, 1880.

Application filed December 17, 1878.

To all whom it may concern:

Be it known that I, ANDREW C. FARN-
SWORTH, of Chicago, in the county of Cook and
State of Illinois, have invented certain Im-
5 provements in Portable Fare-Collecting Appa-
ratus, of which the following is a specifica-
tion.

This invention will be fully understood from
the accompanying drawings and the subjoined
10 description.

In the drawings, Figure 1 is a plan, and
Fig. 2 a side view, of my improved fare-col-
lector. Fig. 3 is a central vertical section of
the same; and Fig. 4, a vertical section upon
15 the line $x-x$ of Fig. 3, facing in the direction
of the arrow. Figs. 5 and 6 are respectively
plan and side views of a modified form of my
apparatus.

Like letters indicate like parts in all the fig-
20 ures in which they are used.

The parts of my apparatus containing the
operative mechanisms of the fare-receiving
platforms, the register, and the bell are in-
closed in a metal cover, A, at the top of which
25 is the funnel A' for the insertion of the fare,
and at the side the handle A², whereby the
conductor holds the apparatus when collecting
the fares. The funnel A' is centrally
placed, as shown.

30 Below the funnel, with the apex formed by
their junction directly at the opening thereof,
are two inclined leaves, B, preferably of hard
rubber or blackened metal, each hinged at
the apex to the side plates, B', and extending
35 down to the plate-glass windows B² at each
side of the apparatus. These windows are
placed at the same inclined plane as the
leaves, and there is formed between them and
the leaves an inclined shallow chamber, C,
40 into which the fare falls as it issues from the
funnel, and wherein it is compelled to lie flat
upon the leaf, directly under the window, and
in such position that it can be inspected to
good advantage. The funnel being so immedi-
45 ately over the windows enables me to utilize
the surface of the funnels to reflect light upon
the coin.

50 By nickel-plating the funnel a surface is ob-
tained which thus aids materially in throw-
ing a strong light upon the coin. The black-
ened background of the leaves also aids in
this result.

The coin, when sufficiently examined, is
dropped by the conductor into a flexible re-
ceiver or bag, D, the lower ends of the leaves 55
being lowered for the purpose by the action of
the vertical rod E and the toggle e, (shown in
Fig. 4 in dotted lines,) connected to the rod
and depressed therewith by the conductor's
thumb. The pivots by which the toggle ends 60
are joined to the leaves work in slots e' in one
of the side plates, B'.

Below the leaves, and between them and the
receiving bag, is an inverted hollow cone-
shaped metal bottom piece, open at its lower 65
center to allow the coin to pass through, but
otherwise closing the operating parts against
access from below. This bottom piece, F, fits the
interior of the cover A, and is suitably fast-
ened thereto by fastenings excluded from the 70
conductor. When the coin drops from the
leaf it is received upon the inclined inner sur-
face of this bottom, and is guided thereby to
the opening into the bag. Below this opening
f, and suspended thereat in such manner that 75
they incline toward each other, and so pre-
vent the re-entrance of coin into the metal
parts of the apparatus by the tipping up of
the same, are two leaves, f', the attachment
to the part F being by means of inclined pins 80
f². These leaves are given a limited amount
of movement upon the pins, by which they at
all times, whatever may be the position of the
apparatus, tend to close the opening f. They
do not impede the entrance of the coin into 85
the bag, but prevent the fraudulent withdrawal
of the same therefrom by reversing the appa-
ratus, and are always an impediment to any at-
tempt at such fraud. When reversed the
gravity will bring them together, and they 90
thus become self-acting. As a further pre-
caution against peculations of this kind, I con-
template using a frame-work of wire, or an
equivalent device, which will surround the
opening f and leaves f² and effectually pre- 95
vent all tampering with the money which has
been deposited in the bag. The bag is se-
cured to the metal parts by a bracelet, G,
locked by any suitable lock sealed to the con-
ductor, and held in a groove in the part A, or 100
upon projections thereon, or in some other
suitable manner.

The usual register H, visible through the
window h, and the bell I, both suitably at-

tached to the thumb-rod E, or connected therewith by mechanism operated thereby, are also employed in my apparatus.

It will be noticed that no obstacle exists to the withdrawal of the coin at any time before it is dropped from the tilting-leaf. This permits the rectification of mistakes before the coin has passed beyond the conductor's control by simply upturning the apparatus.

10 In the modification shown the changes are principally in the shape of the metal parts. By making the back where the handle is attached straight instead of rounding, more room is afforded for the register, and, consequently, 15 greater perfection can be given to the mechanism thereof.

The flexible fare-deposit enables the conductor to carry it in his pocket when not actually using it, and it conforms to the amount 20 of coin in it, taking up only such an amount of room as is required by the accumulated fares. The apparatus is thus rendered less unwieldy than it would be were it rigid in all its parts.

25 By giving the sides of the funnel the same angle or inclination as the leaves B the return of the coin for the correction of mistakes is facilitated.

I claim—

1. In a portable fare-box, a case, A, having 30 a top with two oblique sides, with glazed openings B² and a receiving-funnel, A', at the apex, combined with leaves B, beneath said funnel, and parallel with said oblique top plates, to constitute shallow parallel-sided inspection-chambers C, as shown and described.

2. In a portable fare-box, a case, A, having an oblique-sided top with glazed openings B² and leaves B, parallel therewith, to constitute shallow inspection-chambers C, said leaves being hinged at a point near their proximate edges, combined with a piston, E, and toggle e, whereby said leaves are moved, as set forth.

3. In a portable fare-box, a case, A, having a receiving-slit and inspection-chamber at the 45 top, and a removable receptacle, D, below a funnel-shaped bottom, F, for said case, and a discharge-opening, f, therein, combined with plates f' f', loosely connected to said bottom F, whereby said opening f will be closed and 50 the escape of fares from said receptacle will be prevented when the implement is turned upside down, as set forth.

ANDREW C. FARNSWORTH.
